(57) **CLAIM**

The ornamental design for a bag, as shown and described.

DESCRIPTION

FIG. 1 is an upper left perspective view of an exemplary bag; FIG. 2 is an upper right perspective view of the bag shown in FIG. 1;

FIG. 3 is a front view of the bag shown in FIG. 1;

FIG. 4 is a rear view of the bag shown in FIG. 1;

FIG. 5 is a left side view of the bag shown in FIG. 1;

FIG. 6 is a right side view of the bag shown in FIG. 1;

FIG. 7 is a top view of the bag shown in FIG. 1;

FIG. 8 is a bottom view of the bag shown in FIG. 1;

FIG. 9 is an upper right perspective view of another exemplary bag;

FIG. 10 is an upper left perspective view of the bag shown in FIG. 9;

FIG. 11 is a front view of the bag shown in FIG. 9;

FIG. 12 is a rear view of the bag shown in FIG. 9;

FIG. 13 is a left side view of the bag shown in FIG. 9;

FIG. 14 is a right side view of the bag shown in FIG. 9;

FIG. 15 is a top view of the bag shown in FIG. 9; and,

FIG. 16 is a bottom view of the bag as shown in FIG. 9.

The broken lines shown in the figures are for illustrative purposes only and form no part of the claimed design.

1 Claim, 16 Drawing Sheets
